CROSS CHAIN FOR TIRE CHAINS

Henry St. Pierre, Worcester, Mass.

Application September 9, 1950, Serial No. 12,130

Term of patent 14 years

(Cl. D90—20)

To all whom it may concern:

Be it known that I, Henry St. Pierre, a citizen of the United States, residing at Worcester, county of Worcester, and State of Massachusetts, have invented a new, original, and ornamental Design for a Cross Chain for Tire Chains, of which the following is a specification, reference being had to the accompanying drawing, forming part thereof.

Fig. 1 is a plan view of the cross chain embodying my new design;

Fig. 2 is a view in elevation of the cross chain as shown in Fig. 1;

Fig. 3 is a plan view of certain of the links of Fig. 1 on an enlarged scale; and

Fig. 4 is a view in elevation of one of the elements applied to the links of the cross chain.

I claim:

The ornamental design for a cross chain for tire chains, as shown.

HENRY ST. PIERRE.
